ABRASIVE WHEEL

Joseph Burns, Milwaukee, Wis.

Application August 24, 1938, Serial No. 226,567

2 Claims. (Cl. 51—73)

My invention relates to the art of grinding, polishing and buffing and includes among its objects and advantages the provision of an improved abrasive wheel.

An object of my invention is to provide a device of the type described comprising comminuted abrasive inside a drum rotated at such speed as to provide an abrasive surface for grinding articles. The drum is rotated at sufficient speed to hold the abrasive in pressure relation with the face of the drum through the action of centrifugal forces. The compactness of the body of abrasive about the wall of the drum is determined by the speed of the drum, while the flexibility of the abrasive body at low speeds is such as to readily accommodate itself to articles of different shapes. Rotation of the drum at a relatively high speed will render the abrasive body relatively solid. In processing certain types of articles, the abrasive body may be trued by holding a straight edge thereagainst so as to provide a perfectly smooth abrasive surface. While in most cases the abrasive will be held against the face of the drum and travel at the peripheral speed of the drum, my invention contemplates means for deflecting the comminuted abrasive out of its normal course for processing articles of exceptionally irregular configuration. Since the abrasive takes the configuration of the drum because of centrifugal forces, the cutting properties of the abrasive is not impaired by any vehicle such as glue or rosin.

In the accompanying drawing:

Figure 1 is an end view of the invention with parts of the drum broken away for the sake of clearness; and

Figure 2 is a sectional view along the line 2—2 of Figure 1.

In the embodiment selected to illustrate my invention, I make use of a support 10 which rotatably supports the abrasive containing drum 12. Drum 12 includes a peripheral wall 14 terminating in side flanges 16. Figure 1 illustrates the support 10 as comprising a metal plate 18 shaped to provide an arm 20 having a right-angular reach 22 terminating in a parallel reach 24. Flanged wheels 26 are rotatably mounted on the arm 20 and the reach 24 for lending support to the drum 12. The wheels have rolling relation with the peripheral wall 14 while the flanges of the wheels bear against the flanges 16 of the drum.

Plate 18 includes a plurality of arms 28 which correspond to the reach 22 and are shaped to provide reaches 30 paralleling the plate 18. The

plate and the reaches 30 rotatably support flanged wheels 32 similar to the wheels 26. Figure 1 illustrates the wheel units as being spaced ninety degrees about the peripheral wall 14. A sleeve 34 is formed integrally with the plate 18 and is bored to loosely receive the motor shaft 36. Through the outer end of the motor shaft 36 I connect a pinion 38 which is arranged in mesh with a gear 40 attached to the peripheral wall 14. Thus operation of the motor 42 will rotate the drum 12. Support 10 is maintained in an upright position through the medium of brackets 44 connected with the plate 18 and attached to the motor housing by bolts 46.

In operation the drum 12 is provided with a supply of comminuted abrasive 48. Through rotation of the drum 12 the comminuted abrasive will accumulate in a body about the peripheral wall 14 because of centrifugal forces. The drum 12 together with the flanges 16 is of sufficient diameter to permit articles to be processed to be inserted inside the drum. The abrasive 48 will form an abrasive wall 50 against which articles may be held for grinding, polishing or buffing purposes. The degree of compactness or solidity of the abrasive wall 50 will depend upon the speed at which the drum 12 is rotated. The speed of the drum will depend upon the nature of the work being processed. A low speed will lend looseness to the abrasive wall 50 so that articles may easily be partly embedded therein for grinding, polishing or buffing irregular surfaces. The abrasive wall may be trued by holding a straight edge thereagainst to provide a perfectly smooth surface. Rotation of the drum at an exceedingly high speed will provide an abrasive wall of considerable solidity.

In some cases it may be desirable to deflect the material of the abrasive wall 50 out of its true course for grinding, polishing or buffing various types of articles. Plate 18 may be provided with a right-angular flange 52 to which brackets 54 are fixedly connected, as by welding. Figure 1 illustrates one bracket 54 only but the two brackets are identical in construction and spaced to extend inwardly partly across the ends of the drum for supporting a deflecting plate 56. Plate 56 is curved as at 58 and has its edge 60 lying in abrasive collecting relation with the inner face of the peripheral wall 14.

Rotation of the drum 12 in the direction of the arrow 62 will cause the abrasive to be deflected in a stream 64 and thrown upon the opposite side of the drum, as at 66. Stream 64 may be utilized for many purposes, but in Figure 1 I have

illustrated the stream as being employed for polishing a moldboard 68. Bracket 70 may be employed for lending support to the moldboard 68. Many articles may be supported by hand 5 and held in the path of the stream 64 for grinding, polishing or buffing purposes. Motor 42 includes a base 12 which may be fixedly anchored to any suitable support so as to effectively balance the support 10 and its associated drum 12.

10 Without further elaboration, the foregoing will so fully illustrate my invention that others may, by applying current knowledge, readily adapt the same for use under various conditions of service.

I claim:

15 1. A device of the type described comprising a drum mounted for rotation, said drum including

a comminuted abrasive collecting face, means for rotating the drum, and an abrasive deflecting means located inside the drum for deflecting the abrasive out of its normal course in the form of an abrading stream across the drum for collection on its opposite side. 5

2. A device of the type described comprising a drum having inwardly extending flanges at its ends, the wall of the drum constituting a comminuted abrasive collecting surface, means for 10 rotating the drum, a deflecting plate located inside the drum for deflecting abrasive out of its normal course in the form of an abrading stream across the drum, and a support for said deflecting plate. 10

JOSEPH BURNS.
